JAMES FIDDES AND JOHN FORDYCE WATT, OF ABERDEEN, SCOTLAND, ASSIGNEES TO THE EXPANSION SPRINKLER SYNDICATE LIMITED, OF ABERDEEN, SCOTLAND.

AUTOMATIC SPRINKLER SYSTEM.

No. 877,707.

Specification of Letters Patent.

Patented Jan. 28, 1908.

Application filed February 26, 1907. Serial No. 359,456.

To all whom it may concern:

Be it known that we, JAMES FIDDES and JOHN FORDYCE WATT, subjects of the King of the United Kingdom of Great Britain and 5 Ireland, and residing at Aberdeen, Scotland, have invented certain new and useful Improvements in Automatic Sprinkler Systems, of which the following is a specification.

This invention relates to automatic 10 sprinkler systems in which air compressed into sprinkler supply pipes serves normally to exclude water from the same.

In systems of the above type the water is 15 only released when the fusible sprinkler head has been opened by the action of fire and the compressed air in the supply pipes escapes from the sprinkler head at the seat of the outbreak.

The invention has for its object to effect 20 the quick and automatic release of the compressed air on outbreak of fire so that the water will be in the sprinkler supply pipes ready to attack the fire immediately the sprinkler head is opened.

25 The invention consists of an attachment connected to an automatic fire alarm system of the type in which fluid under pressure is contained in narrow tubing carried throughout the building to be protected. A branch 30 connection is taken from the end of the sprinkler supply pipes furthest from the main water valve, said branch being normally kept closed by means of a valve operated on the action of an automatic fire detector, the valve connection being so arranged 35 that while it allows the compressed air to be exhausted water is not allowed to flow through it.

In the accompanying drawings which 40 illustrate the invention, Figure 1 is a sectional elevation of part of a sprinkler system embodying our improvements and Figs. 2 and 3 are vertical sections of forms of air outlet valves that may be employed in place of that 45 shown at Fig. 1.

As shown, we place a diaphragm valve A between the junction B to the sprinkler supply pipes and an outlet branch C, said diaphragm valve A being connected to a pneu-

matic alarm system in which air is held 50 under compression in seamless metal tubing B¹ of small diameter.

The compressed air in the tubing B¹ passes through a valve B² and acts on the diaphragm valve A to keep the same on its seat 55 a thus preventing the passage of air to the outlet C. Near the outlet C or at any other convenient point between the diaphragm valve and said outlet is placed a valve c so arranged that it allows the escape of the compressed air and closes by the flow of water that follows on the release of the compressed air in the sprinkler supply pipes.

The action of the arrangement is as follows:—On an outbreak of fire the compressed 65 air in the tubing B¹ is released by fracture of a frangible air outlet. The diaphragm valve A is lifted from its seat a by the air pressure in the sprinkler supply pipes and allows the air to escape at the large outlet C; the resulting flow of water, after the air pressure has been reduced to a minimum, causes the valve c to close and prevents the exit of water through the outlet C. The arrangement described thus permits the rapid release 70 of the air in the sprinkler pipes and permits the pipes to fill immediately with water so that when the sprinkler heads open the water is ready to attack the fire instead of being held back until the compressed air has escaped through the open sprinkler head.

What we claim is:—

The herein-described automatic sprinkler system comprising, in combination, piping B connected to a source of water supply but 85 containing compressed air for normally excluding water from said piping, a branch pipe C connected to said piping and having a large outlet, a diaphragm valve A normally preventing passage of compressed air 90 from said piping B to said branch pipe C, tubing B¹ normally containing compressed air but arranged to release such compressed air on outbreak of fire, a valved connection between said tubing B¹ and said diaphragm 95 valve A, whereby said diaphragm valve is normally subjected to the action of air pressure on both sides but is relieved on one side

on escape of air from said tubing B¹ so as to be lifted by the air in the piping B and a valve c permitting passage of air from said piping B through said outlet C but adapted 5 to prevent the passage of water through said outlet.

In testimony whereof we have signed our

names to this specification in the presence of two subscribing witnesses.

JAMES FIDDES.
JOHN FORDYCE WATT.
